INSPECTING WIRE DRAWING DIE

Robert Henry Saviers, Morrisville, Pa., assignor to
The American Steel and Wire Company of New
Jersey, a corporation of New Jersey

Application September 15, 1944, Serial No. 554,304

2 Claims. (Cl. 18—55)

1

This invention is concerned with inspecting wire drawing dies to determine whether their various parts are properly made.

A specific example of the invention is illustrated by the accompanying drawings, in which:

Figure 1 is a vertical section of apparatus suitable for carrying out the invention;

Figure 2 is a longitudinal section of a die; and

Figure 3 is a detail involved in inspecting the die of Figure 2.

More specifically, these drawings illustrate a tungsten carbide die having the usual steel shell 1, with a ground and polished cylindrical outside, mounting the tungsten carbide insert 2 in which the die hole is formed to provide the bell section 3, the smoothing out section 4, the constricted bearing section 5 and the countersunk section 6, with the ends 7 and 8 of the steel shell 1 ground and polished to form right angular planes respecting the cylindrical outside of the steel shell 1 and the axis of the die hole, and with the die hole axis concentric with the axis of this cylindrical outside. These various parts bear these relative relations, and the various sections have predetermined shapes and a proper finish, in the case of a properly made die, and deviations, characterizing an improperly made die, cause wire drawing trouble. Therefore, it is desirable to inspect such wire drawing dies to determine whether they are properly made.

According to the present invention, a metal cylinder 9 is provided with an internal bore 10 that is ground and polished to fit the outside of the steel shell 1, of the die, as closely as is possible while permitting the die to slide in the bore. This cylinder 9 is then set on end, on the ram 11 of a vertically acting press, with the bottom end of the bore 10 closed by a cylindrical metal plug 12 having at least its top surface ground and finished as truly as possible at right angles to its side and with the latter ground and polished to fit the inside of the bore 10 as does the steel shell 1 of the die. Thermoplastic material 13 is then placed in the bore 10 on top of the plug 12, a separator 14 is stuffed into the bearing section of the wire drawing die, with this separator made of material inert to the thermoplastic material 13, the die is then slid into the bore 10, on top of this thermoplastic material 13, more of this material is placed on top of the die, inside the bore 10, and a cylindrical metal piston 15, having its side ground and finished to fit the bore 10, in the same fashion as described in connection with the plug 12 and the die, and with at least its bottom surface ground and finished in

2

the same manner as the top of the plug 12, is then slid in the bore with this bottom surface on the material. The thermoplastic material 13 may be one of the synthetic resin products, commonly used for the purpose of mounting metal specimens for microscopic examination, which are provided the art in the form of a powder which becomes plastic when properly heated. The resin product may be either of the type which is permanently thermoplastic or which becomes infusible after heating and compression, and is preferably opaque. Furthermore, the press, providing the ram 11, may be a specimen mounting press of the type commercially available for mounting metal specimens in such plastic material for microscopic examination.

Continuing, heat is next applied the thermoplastic material 13, as by means of a heater 16 encircling the outside of the cylinder 9, and pressure is applied to the thermoplastic material on both sides of the die and directed toward the die, as by operation of the ram 11 so that it raises until the top of the piston 15 contacts an immovable crosshead 17, force being applied to the ram 11 in any fashion. The pressure applied to the material 13, on opposite sides of the die, should be sufficient so that as the material becomes plastic, due to its heating by the heater 16, it is forced against both ends of the die and into the die hole thereof under adequately heavy pressure to assure complete contact of the material with all parts of the die which it can possibly contact. The manufacturers of synthetic resin thermoplastic products provide instructions as to the temperature and pressure their use requires, and these instructions may be followed in determining the proper temperature and pressure required to mold the plastic masses firmly against both ends of the die and into its die hole.

40 After properly carrying out the above phase, the pressure is released by lowering the ram 11 and the material is cooled as by turning off the heater 16. After cooling, the piston 15 is withdrawn from the cylinder 9 and the molded plastic impressions, resulting from the described procedure, are removed from the cylinder 9. These molded impressions will be found to be stuck to both sides of the die, and by pulling gently on them they can be separately removed axially of the die hole due to the separator 14 separating the impressions at the die hole bearing section. Incidentally, this separator may be satisfactorily made from cotton since this has been found to be non-reactive to most synthetic resin thermoplastic materials.

Now, since the side of the plug 12, the outside of the steel shell 1, of the die, and the piston 15 all formed precision fits with the bore 10, and since the top of the plug 12 and the bottom of the piston 15 were, within precision limits, at true right angles to the various cylindrical parts, the separated impressions may be set on the flat mounting stage of a projection microscope and examined for any deviations from that relationship of the parts which should prevail if the die is properly made. Thus, in the case of the illustrated impression, the bottom 18 represents a flat surface that is at right angles to the cylindrical outside of the steel shell 1. The opposite surface 19 of this impression is parallel to the surface 18 only in case the end 7 of the steel shell of the die was at right angles to the shell's cylindrical outside. The die hole portion of the impression provides a means for determining whether the die hole is axially concentric with the cylindrical outside of the steel shell 1, this being done by measuring whether the axis of the die hole impression is at right angles to the bottom of the impression and by rotation of the impression to determine offset. Finally, the die hole portion of the impression provides a means for measuring the diameters and angularities of the various die hole sections, since the part 20 of the impression was molded by the bell 3 of the die, the longer tapering portion 21 was molded by the smoothing out section 4, while the fragmentary nib 22 was molded by the bearing section. As previously explained, it is considered best to examine the impression by means of a projection microscope of the type casting an enlarged silhouette of the specimen on a screen for direct inspection and measurement.

Although the foregoing explains the mode of inspecting the entrance end of the die, it is obvious that the other impression taken from the exit end of the die provides a means for inspecting that end.

I claim:

1. A method of inspecting the die hole of a wire drawing die, said die having a shell with a cylindrical outer surface, the shell mounting an insert in which the die hole is formed concentric with the outer surface of the shell, the die hole having a constricted bearing section inwardly of the ends thereof, said method comprising inserting a separator to which thermoplastic resin is non-reactive completely across the die hole constricted bearing section, placing the die in a mold having a cylindrical bore closely fitting the outer cylindrical surface of the shell, the die being placed in the mold intermediate the ends of such mold, inserting thermoplastic resin in

the mold at both ends of the die in amounts more than sufficient to fill the respective ends of the die hole, applying pressure and heat to such resin by means of surfaces at right angles to the bore 5 of the mold to force the resin against the die ends and into the die hole, to make an impression of the die hole that is separable into two parts for removal, because of said separating material, releasing such pressure, removing the die 10 from the mold, and removing the two plastic impressions when solidified axially from the die hole.

2. A method of inspecting the die hole of a wire drawing die, said die having a shell with a cylindrical outer surface, the shell mounting an insert in which the die hole is formed concentric with the outer surface of the shell, the die hole having a constricted bearing section inwardly of the ends thereof, said method comprising inserting a separator to which thermoplastic resin is non-reactive completely across the die hole constricted bearing section, placing the die in a mold having a cylindrical bore closely fitting the outer cylindrical surface of the shell, 20 the die being placed in the mold intermediate the ends of such mold, inserting thermoplastic resin in the mold at both ends of the die in amounts more than sufficient to fill the respective ends of the die hole, applying pressure and heat to such resin by means of surfaces at right angles to the bore of the mold to force the resin against the die ends and into the die hole, to make an impression of the die hole that is separable into two parts for removal, because of said separating 25 material, releasing such pressure, removing the die from the mold, and removing the two plastic impressions when solidified axially from the die hole, the quantity of resin introduced into the mold on each side of the die being sufficient to form pedestals on the ends of the plastic impressions of the die hole.
